United States Patent Office

Des. 222,097
Patented Sept. 28, 1971

222,097

CANISTER OR SIMILAR ARTICLE

David Douglas, 1332 S. 26th St.,
Manitowoc, Wis. 54220

Filed Sept. 22, 1969, Ser. No. 19,232

Term of patent 14 years

Int. Cl. D7—01

U.S. Cl. D44—6

Fig. 1

Fig. 2

Fig. 3

Fig. 4

FIG. 1 is a side elevational view of a canister or similar article showing my design;

FIG. 2 is a top plan view;

FIG. 3 is a bottom plan view; and

FIG. 4 is a sectional view taken along line 4—4 of FIG. 2.

I claim:

The ornamental design for a canister or similar article, substantially as shown.
